UNITED STATES PATENT OFFICE.

BURT A. PETERSON, OF ROCKFORD, ILLINOIS, ASSIGNOR TO HOWARD D. COLMAN, LUTHER L. MILLER, AND HARRY A. SEVERSON, COPARTNERS DOING BUSINESS AT ROCKFORD, ILLINOIS, AS BARBER-COLMAN COMPANY.

MEANS FOR ATTACHING DOFFER-SUPPORTING RAILS TO SPINNING-FRAMES.

1,070,840.

Specification of Letters Patent. Patented Aug. 19, 1913.

Application filed May 24, 1911, Serial No. 629,133. Renewed February 20, 1913. Serial No. 749,729.

To all whom it may concern:

Be it known that I, BURT A. PETERSON, a citizen of the United States, residing at Rockford, in the county of Winnebago and State of Illinois, have invented certain new and useful Improvements in Means for Attaching Doffer-Supporting Rails to Spinning-Frames, of which the following is a specification.

10 When in use, spinning-frame doffers of the portable type are supported upon rails attached to and extending along the front of the spinning frames. The rails have been connected to the frames by means of clips.

15 This invention relates to the construction of the clips and more particularly to the means for securing the clips to the spinning frame.

Certain features of the construction here-
20 in disclosed are claimed broadly in my co-
pending application Serial No. 631,042, filed
June 3, 1911.

In the accompanying drawings, Figure 1
25 is a transverse vertical sectional view
through the spindle rail of a spinning
frame, showing a doffer-supporting rail
secured to the spindle rail by means embody-
ing my invention. Fig. 2 is a top plan view
30 of the parts shown in Fig. 1.

35 The drawings represent at 1 a portion of
the ladder or spindle rail of a spinning
frame, 2 being the spindles and 3 being a
doffer-supporting rail of any suitable form.
The doffer rail is secured to the spindle rail
35 at intervals in its length by means of clips 4
each formed from a strip of metal, and each
comprising a flat portion adapted to lie in
contact with the top of the spindle rail be-
tween two adjacent spindles.

40 The forward portion of each clip com-
prises means for supporting and securing
the doffer rail 3. Said means comprises a
vertical downwardly-extending portion 5
and a portion 6 extending forwardly from
45 the lower end of said vertical portion, the
portion 6 forming a seat for the doffer rail.
The latter is held rigidly upon its seat with
one side of the rail in contact with the ver-
tical portion 5 by means of hooks 7 prefer-
ably formed by shearing away a portion of
50 the sides of the strip forming the clip, and
bending the free ends so obtained to form
hooks, as shown. In the manufacture of the
clip, the hooks 7 are not bent as far as

shown in the drawings, but are left extend- 55
ing outwardly far enough so that the doffer
rail can be inserted laterally onto its seat 6.

The rear or inner end of the clip com-
prises a downwardly extending portion 8
and a portion 9 extending forward from the 60
lower end of the portion 8 sufficiently to
underlie the web 1^a of the ladder rail 1. A
clamp screw 10 extends horizontally through
the portion 8 and is arranged to bear against
the rear edge of the spindle rail. A similar 65
screw 11 extends through the portion 9 into
contact with the lower edge of the web 1^a.
It will be seen that the screw 10 holds the
clip in firm contact with the front edge of
70 the spindle rail, and that the screw 11 holds
the clip securely down upon the top of the
spindle rail.

When a doffer rail is to be attached to a
spinning frame, a suitable number of clips 4
are placed upon the spindle rail and firmly 75
secured thereto by tightening up the screws
10 and 11. The doffer rail is then inserted
sidewise onto the seats 6 of the clips, and
the hooks 7 driven down to the position in-
dicated in Fig. 1 to lock the doffer rail 80
rigidly in place. The distance between the
center line of the spindles and the front
edge of the spindle rail varies in different
spinning frames, and when necessary a shim
85 (not shown) may be placed between the
portion 5 of the clips and the front edge of
the spindle rail, so as to space the doffer
rail the proper distance from the spindles.

I claim as my invention:

1. The combination, with the spindle rail 90
of a spinning frame, of a doffer-supporting
rail, and a clip extending across the top of
the spindle rail and having a portion at its
forward end to carry said doffer-supporting
rail, said clip having a portion at its rear 95
end underlying the spindle rail, and a ver-
tical screw seated in the last mentioned por-
tion and bearing against the lower side of
the spindle rail to clamp the clip down
firmly on said rail. 100

2. The combination, with the spinning
rail of a spinning frame, of a clip compris-
ing a portion extending across the top of the
spindle rail and further comprising a down-
wardly extending portion at each end of 105
said other portion, a doffer-supporting rail
secured to one of said downwardly extend-
ing portions, and two screws seated in the

other downwardly extending portion, one of said screws being horizontally disposed and arranged to bear against a rear edge of the spindle rail, and the other screw being vertically disposed and arranged to bear against the lower side of the spindle rail.

3. The combination, with the spindle rail of a spinning frame, of a clip formed from an integral strip of metal and comprising a portion extending across the top of the spindle rail, a portion extending downwardly in front of the spindle rail, and a portion extending downwardly in the rear of the spindle rail, the lower end of the last mentioned portion being bent into a substantially horizontal plane, a screw extending

horizontally through said rear downwardly extending portion and arranged to bear against the rear edge of the spindle rail, a screw extending vertically through said horizontal portion and arranged to bear against the lower side of the spindle rail, and a doffer-supporting rail secured to the downwardly extending portion in front of the spindle rail. 25

In testimony whereof I affix my signature in presence of two witnesses.

BURT A. PETERSON.
